DESIGN FOR A PLAYGROUND APPARATUS

Peter A. Cosme, Chicago, Ill., assignor to Sears, Roebuck and Co., Chicago, Ill., a corporation of New York

Application July 11, 1945, Serial No. 120,644

Term of patent 7 years

(Cl. D34—5)

To all whom it may concern:

Be it known that I, Peter A. Cosme, a citizen of the United States of America and a resident of Chicago, county of Cook, and State of Illinois, have invented a new, original, and ornamental Design for a Playground Apparatus, of which the following is a specification, reference being had to the accompanying drawing, forming a part thereof.

The sole figure is a perspective view of a playground apparatus showing my new design.

The essential features of the playground apparatus reside in the portions shown in full lines on the drawing.

I claim:
The ornamental design for a playground apparatus, substantially as shown and described.

PETER A. COSME.
